UNITED STATES PATENT OFFICE.

DANIEL DRAWBAUGH, OF CAMP HILL, PENNSYLVANIA, ASSIGNOR OF ONE-HALF TO
WILLIAM C. BOWMAN, OF LEMOYNE, PENNSYLVANIA.

COIN-ASSORTER.

989,238.

Specification of Letters Patent. Patented Apr. 11, 1911.

Application filed December 12, 1910. Serial No. 596,806.

To all whom it may concern:

Be it known that I, DANIEL DRAWBAUGH, a citizen of the United States, residing at Camp Hill, in the county of Cumberland and State of Pennsylvania, have invented 5 certain new and useful Improvements in Coin-Assorters, of which the following is a specification.

This invention relates to improvements in 10 the type of coin assorter illustrated in my co-pending application Serial No. 587,643, filed October 17, 1910. In said application I have shown an assorter comprising a receiver into which the mixed coins are 15 dumped, said receiver consisting of a series of perforated diaphragms, mounted upon an inclined shaft, through which diaphragms the coins may sift and become assorted according to size, said diaphragms having 20 affixed to their upper surfaces spirally arranged retaining flanges or wings which retain the coins upon the diaphragms while the receiver is being rotated in one direction and permit them to discharge from the diaphragms while the receiver is being rotated 25 in the reverse direction; a series of coin tubes, slides for conveying the coins from the diaphragms to the tubes, and delivery apparatus for ejecting the coins from the 30 tubes, one coin at a time.

In my present invention, instead of employing the fixed spirally arranged flanges above referred to, I provide the receiver with a peripheral wall composed, in part, of 35 movable gates, and connections between said gates and the operating shaft whereby when the shaft and receiver are turned in one direction to sift the coins, the gates will be automatically closed, and when turned in 40 the opposite direction the gates will automatically open and release the coins.

The present invention also embodies improvements in the delivery apparatus whereby a plurality of coins are delivered from 45 the coin tubes at each operation.

In the accompanying drawing, which illustrates my invention, Figure 1 is a perspective view of the assorter; Fig. 2 is a section through one of the coin tubes, 50 taken above the foot plate; Fig. 3 is a vertical section through portions of several slides, showing one of the straps connecting the slides; Fig. 4 is a top plan view of the assorter, some of the details 55 being omitted; Fig. 5 is a view showing the

assorter partly in side elevation and partly in vertical section, the lower portions of the tubes being omitted; Fig. 6 is a perspective view of one of the clips upon which the supporting rods for the foot plate rest; Fig. 7 is a side view, partly broken away and partly in section, of one of the coin tubes; Fig. 8 is a section through one of the tubes on the line 8—8 of Fig. 7; Fig. 9 is a section on the line 9—9 of Fig. 7; Fig. 10 is a section on the line 10—10 of Fig. 7, showing the delivery mechanism in plan view; Fig. 11 is an inverted plan view of the delivery mechanism; and, Fig. 12 is a top plan view of the lever with pocket attached for delivering the coins from the coin tubes.

Referring to the drawing, A indicates a suitable table or support to the top of which is secured a bearing block 1 in which is mounted a stud or shaft 2 and upon said shaft is journaled a base 3 which forms a support for the assorter. The assorter comprises, in general, a cylindrical receiver B, rotatably mounted upon the base 3, as hereinafter more fully described, a series of 80 slides C and a series of coin tubes D; said slides leading from the receiver to the tubes. The tubes are supported near their lower ends by a foot plate or cross piece 4 which is connected by rods 5 to the base 3, said rods having a bearing intermediate their ends, in forked clips 6 which are secured to the table A. The tubes extend through notches cut in the forward edge of the foot plate and are provided with collars f which rest upon said foot plate. These collars, as shown in Figs. 1, 2, 7 and 8, are bent downwardly on the forward side and latches g pivoted to the foot plate bear against the turned-down faces of the collars and hold the tubes within the notches. Pins h in the foot plate engage notches i in the collars and prevent the tubes from turning. The slides are connected together and braced by metal bands or straps j having inwardly bent 95 hooks j' which extend over the edges of the slides. One of these straps is shown in Fig. 1.

The coin receiver B is cylindrical in form, open at the top, and contains a series of 100 foraminous diaphragms or trays b, b', b'', b'', b'', and a bottom diaphragm b'' which may be unperforated. A sleeve 7 extends through the center of the receiver and is journaled upon a shaft 8 which shaft, in 110

turn, extends through and is journaled in the base 3. The shaft is inclined, as shown, so that the diaphragms b , b' , etc., in the receiver incline toward the slides c , c' , etc., which are arranged in the planes of the diaphragms and incline toward the mouths of the tubes d , d' , etc., with which they respectively connect. The peripheral wall of the receiver B is composed of alternate sections 9, extending the full height of the receiver and fixed to the edges of the diaphragms or trays, and intermediate sections 10 of slightly less width than the distance between the trays, which latter sections are secured to rods 11 extending through openings in the trays and connected at their lower ends to levers 12 which levers are connected by links 13 to a collar or wrist plate, 14, secured to the shaft 8 by suitable means, such as the set screw 15. The wrist plate 14 rests upon the base 3 and the sleeve 7 rests upon the wrist plate, as shown in Fig. 5. The rods 11 are located at the ends of the fixed sections 9 of the wall of the receiver and the sections 10, secured to said rods are of sufficient length to extend from the end of one section 9 to a point a little beyond the end of the succeeding section 9, so as to over-lap the latter, as shown in Figs. 1 and 4. The arrangement is such that if the receiver is held stationary and the crank 16 on the shaft 8 is turned in one direction, the sections 10 of the wall will be turned so that their free ends will rest against the sections 9 and form a continuous peripheral wall, as shown in full lines in Figs. 1 and 4, whereas, if the handle 16 is turned in the opposite direction the receiver being held stationary, the sections 10 will be swung inward, as shown in dotted lines in Figs. 1 and 4, thus breaking the continuity of the peripheral wall and providing outlets for the coins between the sections 9. The sections 10 thus form gates which may be opened or closed, according to the direction of rotation of the handle 16. A stop pin 17 is secured to the under side of the receiver and the collar or wrist plate 14 is cut away on its periphery to provide shoulders 18 and 19, as shown in dotted lines in Fig. 1, to limit the relative movement of the receiver and the shaft 8, collar, and the gates connected to the collar by the links and levers.

The openings 20 in the diaphragms or trays diminish in size from the uppermost tray downward, these openings being of such size that the coins of smallest diameter may fall through the successive openings to the lowermost diaphragm b' , while coins of the next larger size will be caught on the diaphragm b' , and so on. For United States coins, for instance, dollars will be retained on the diaphragm b , halves on the diaphragm b' , quarters on the dia-

phragm b'' , five cent pieces on the diaphragm b'' , pennies on the diaphragm b'' and dimes on the diaphragm b'' .

The slides c , c' , etc., are all of triangular form with upright sides 21 for guiding the coins from the diaphragms or trays to the tubes d , d' , etc., each slide, at its forward end, having a downwardly turned spout or outlet 22, which fits into the flaring mouth 23 of the tube. At the lower end of each tube is a stop 24, hereinafter more fully referred to, which supports the coins when delivered into the tube.

In operation, assuming the gates 10 to be closed, when an assortment of coins is dumped into the receiver, the handle 16 is turned first in the direction to keep the gates closed, and as the shaft and receiver rotate the coins sift through the receiver and are retained on the proper diaphragms, one or two turns of the receiver being sufficient to insure the proper location of the coins. The handle is then given a reverse movement, which causes the gates to swing open and the receiver to rotate in the reverse direction and, as will be apparent, the coins will gravitate from the diaphragms onto the slides c , c' , etc., and thence into their respective coin tubes. The assortment of the coins according to size is thus accomplished very quickly. Each tube has a collar 25 secured to its lower end and the stop plate 24 is rigidly secured to this collar by a stud or post 26 passing through both. Between the collar 25 and the stop plate 24 is arranged a short section of tubing 27 surrounded at its upper end by a collar 28, from which projects a hand lever 28, which lever is pivoted upon the stud 26 and is connected by a helical spring 29 to the stop plate 24. The collar 25 has a depending pin or lug 30 and the lever 28 has shoulders 31 and 32 adapted to engage the lug and limit the movement of the lever. The spring 29 normally tends to hold the lever and the tubular part 27 so that the latter will register with the coin tube to permit the coins to pass through onto the stop plate 24. By moving the lever against the tension of the spring, the tubular part 27 is carried outwardly beyond the curved edge 24 of the stop plate and the coins within said tubular part will then drop out into cartons or receptacles located so as to receive them. The collar 28 has an extension 28^a at one side arranged so that when the lever is moved to swing the tubular pocket 27 out of line with the coin tube, the extension 28^a of the collar will be carried under the tube and form a support for all of the coins above the pocket 27 while the latter is moving to the delivery point.

The distance between the stop plate 24 and the collar 25 at the end of the delivery tube varies according to the number of coins 130

and the thickness of the coins which it is desired to deliver at any one operation from any given tube. Thus, if it is desired to deliver ten coins from one of the tubes, the 5 distance between the collar 25 and the stop plate 24 will be slightly greater than the thickness of ten coins, but not as great as the thickness of eleven coins and the lever 28 is preferably mounted so that the pocket 10 can rock slightly in a vertical direction. This is to allow for slight differences in the thickness of coins of the same denomination, so that ten coins, and no more, may enter the tubular pocket 27 and when the lever 15 is turned to move the latter the movement will not be stopped by a coin in the lower end of the tube engaging the upper edge of the pocket. The machine shown in the drawing is arranged for United States coins 20 and each pocket except the pocket below the five-cent and one-cent tubes is arranged to receive and deliver ten coins. The pocket below the five-cent tube d^3 is shown longer than the others and is intended to receive 25 and deliver twenty five-cent pieces, while the pocket beneath the one-cent tube d^4 is short and is intended to receive and deliver five pennies, these quantities of coins of these denominations being found most suitable for 30 stacking purposes. Each pocket therefore receives and delivers five coins or some multiple of five.

What I claim is:—

1. In a coin assorter, a receiver movable in 35 two directions and having inclined perforated diaphragms, gates in the wall of said receiver, and means for automatically opening said gates when the receiver is moved in one direction, and for closing said gates 40 when the receiver is moved in another direction.

2. In a coin assorter, a receiver having inclined perforated diaphragms, gates in the 45 wall of said receiver, means for rotating said receiver, and connections between said means and said gates for automatically opening said gates when the receiver is turned in one direction and for closing said gates when the receiver is turned in the opposite direction.

3. In a coin assorter, a rotatably mounted receiver having perforated diaphragms, gates in the wall of said receiver, and means for automatically opening said gates when the receiver is turned in one direction and for closing said gates when the receiver is turned in the opposite direction.

4. In a coin assorter, a receiver mounted to rotate about an inclined axis, said receiver 60 having a series of perforated diaphragms, gates in the wall of the receiver, and means for automatically opening the gates when the receiver is turned in one direction, and for closing said gates when the receiver is 65 turned in the opposite direction.

5. In a coin assorter, an operating shaft and means for rotating the same, a receiver, having perforated diaphragms, journaled upon said operating shaft, gates in the wall of said receiver, and connections between 70 said gates and shaft for automatically opening the gates when the shaft is turned in one direction and for closing the gates when the shaft is turned in the opposite direction.

6. In a coin assorter, an operating shaft 75 and means for rotating the same, a receiver, having perforated diaphragms, journaled upon said operating shaft, gates in the wall of said receiver, a shaft to which said gates are secured, and connections between said 80 latter shaft and the operating shaft for opening the gates when the operating shaft is turned in one direction and for closing the gates when the operating shaft is turned in the opposite direction.

7. In a coin assorter, an operating shaft and means for rotating the same, a cylindrical receiver journaled upon said shaft, said receiver having a series of superposed perforated diaphragms, gates in the wall of 90 said receiver, one gate above each diaphragm, a shaft connecting said gates, a lever connected to said latter shaft, and a link connecting said lever with the operating shaft.

8. In a coin assorter, an operating shaft and means for rotating the same, a cylindrical receiver journaled upon said shaft, said receiver having a series of superposed perforated diaphragms, a plurality of gates 100 in the wall of said receiver, one gate above each diaphragm, shafts to which said gates are connected, levers connected to said shafts, and links connecting said levers with the operating shaft.

9. In a coin assorter, an operating shaft and means for rotating the same, a cylindrical receiver journaled upon said shaft, said receiver having a series of superposed perforated diaphragms, a plurality of gates 110 in the wall of said receiver above each diaphragm, shafts to which said gates are connected, levers connected to said shafts, a collar or wrist plate connected to the operating shaft and links connecting said wrist 115 plate with said levers.

10. In a coin assorter, a receiver comprising a peripheral wall and superposed perforated diaphragms therein, said wall comprising one or more gates adapted to swing 120 in planes parallel with the diaphragms.

11. In a coin assorter, a receiver comprising a peripheral wall and superposed perforated diaphragms arranged therein, said wall comprising alternate sections in fixed 125 relation to the diaphragms, and intermediate sections movable in planes parallel with the diaphragms and forming gates in said peripheral wall.

12. In a coin assorter, a receiver comprising 130

ing a peripheral wall and superposed perforated diaphragms arranged therein, said wall comprising parts adapted to swing inwardly over the diaphragms in planes parallel with the diaphragms and forming gates in said peripheral wall.

13. In a coin assorster, a receiver mounted to rotate on an inclined axis and comprising a peripheral wall and superposed perforated diaphragms arranged therein, said wall comprising parts adapted to swing inwardly over the diaphragms in planes parallel therewith, and forming gates, a series of slides arranged adjacent such diaphragms, and coin tubes arranged to receive the coins from said slides.

14. In a coin assorster, a receiver mounted

to rotate on an inclined axis and comprising a peripheral wall and superposed diaphragms arranged therein, said wall comprising parts forming gates, means for automatically closing said gates when the receiver is rotated in one direction and for automatically opening the gates when the receiver is rotated in the opposite direction, slides arranged adjacent said diaphragms, and coin tubes arranged to receive the coins from said slides.

In testimony whereof I affix my signature, in presence of two witnesses.

DANIEL DRAWBAUGH.
